UNITED STATES PATENT OFFICE.

GEORGE ADOLPH STEINER, OF SALT LAKE CITY, UTAH, ASSIGNOR, BY MESNE ASSIGNMENTS, TO STEINER SALES COMPANY, OF SALT LAKE CITY, UTAH, A CORPORATION OF UTAH.

TOWEL CABINET.

Application filed May 14, 1920, Serial No. 381,443. Renewed August 1, 1923.

To all whom it may concern:

Be it known that I, GEORGE A. STEINER, a citizen of the United States, resident of Salt Lake City, county of Salt Lake, State of 5 Utah, have invented certain new and useful Improvements in Towel Cabinets, of which the following is a specification.

The object of my invention is to simplify and improve the towel cabinet shown and 10 described in my pending application for Letters Patent of the United States, Serial No. 262,658, filed November 15, 1918.

My present practice is to dispense with all unnecessary parts to reduce the cost of 15 manufacture and also for the purpose of eliminating any mechanism which might become easily disarranged and interfere with the smooth, convenient operation of the cabinet.

20 A further object is to combine simplicity of construction and ease of operation with a feeding arrangement which will wind up the soiled portion of the towel proportionately with the unwinding of the clean portion and at all times prevent contact of the 25 clean and soiled portions to the end that the device will be thoroughly sanitary under all conditions of use.

Other objects of the invention will appear 30 from the following detailed description.

In the accompanying drawings forming part of this specification,

Figure 1 is a front elevation of a towel cabinet embodying my invention,

35 Figure 2 is a vertical sectional view on the line 2—2 of Figure 1,

Figure 3 is a vertical sectional view on the line 3—3 of Figure 1,

Figure 4 is a detail sectional view on the 40 line 4—4 of Figure 3.

In the drawings, 2 represents the side walls of the cabinet and 3 and 4 cross bars at the back of the cabinet and 5 a cross bar at the front thereof. The cabinet is open at 45 the top and bottom and may be provided with screw eyes 6 for hanging it on the wall. The side walls are preferably provided with vertical guide ways 7 extending to a point near the bottom of the cabinet and a frame 50 8 is mounted to slide vertically between said side walls and has bearings for feed rollers 9 and 10 mounted therein, one of said rollers having an operating knob 11 which projects through a vertical slot 12 in one of the 55 side walls. By means of this knob the feed

rolls may be revolved to operate the winding and unwinding rolls. The shafts of the feed rolls are provided with sprockets indicated by dotted lines in Figure 3 and a drive chain 13 engages said sprockets for operating the feed rolls simultaneously and at the same speed, a dog 14 being provided to prevent backward movement of the feed rolls. These rolls are of the same diameter so that the winding and unwinding rolls will be operated at uniform speed.

15 represents the lower or clean towel roll, having gudgeons 16 adapted to slide in the guides 7 and normally rest in the lower ends thereof. 17 is the soiled towel roll, having 70 gudgeons 18 adapted to slide in the upper portion of the guideways. The side walls are also provided with substantially horizontal guideways 19 communicating with the guideway 7 a short distance above the 75 lower ends thereof for the purpose of allowing the convenient insertion and removal of the lower or clean towel roll without the necessity of removing the soiled towel roll and the feed rolls from the upper portion of the 80 guideways. The frame supporting the feed rolls is preferably provided with little knobs or balls 20 adapted to slide on the inner face of the walls 2 and prevent the frame from 85 tilting while the cabinet is in use.

I prefer to provide a cross bar 21 at the lower end of the cabinet to brace and strengthen the same, and the loop of towel extends down under this bar and up in the rear of the cabinet to the soiled towel roll 90 in the top thereof. To prevent the person inserting the clean towel in the cabinet and connecting it with the soiled towel roll from passing the end of the towel over and adjacent the upper feed roll, I provide upright 95 bars 22 mounted in the rear of the feed roll carrying frame and extending over the lower portion thereof to the top of the cabinet. These bars are so positioned that when a clean towel is put in the cabinet, it will be necessary for the operator to carry the loose end of the towel up between these bars and the rear wall of the cabinet and over the top horizontal guide bar before he can attach the towel to the soiled towel roll.

100 In using the cabinet, the clean towel roll with the towel wound thereon is placed in the lower portion of the guideways and unrolled sufficiently to form a loop below the cabinet and the loose end of the towel car- 105 110

ried to the rear of the cabinet then up over the guide bar to the soiled towel roll in the top of the cabinet, the weight of the soiled towel roll and the feed rolls being sufficient 5 to retard the unwinding of the clean towel roll, enabling the user to revolve the roll sufficiently to obtain the desired supply of clean towel, or he may operate the knob and revolve the feed rolls to obtain the same result. As fast as the clean towel roll is unwound, a corresponding portion through the action of the feed rolls will be wound on the soiled towel roll in the top of the cabinet, and this operation will continue until the 10 clean towel is exhausted and when that occurs, the soiled towel will be wound on the top roll and can be readily removed from the cabinet and returned to the laundry. The feed rolls will have suitable friction 15 surfaces to cause them to adhere to the towel and operate the rolls on which it is wound. As the towel on the roll at the bottom of the cabinet is unwound, and the roll becomes lighter, the weight thereon will 20 increase due to the accumulation of the soiled towel on the roll in the top of the cabinet.

I claim as my invention:

1. A towel cabinet comprising a casing 30 having guideways therein, a soiled towel roll and a clean towel roll movable in said guideways, a frame and feed rolls in said frame mounted between said soiled towel and clean towel rolls, a driving connection 35 between said feed rolls, and means mounted on said frame and contacting with the side

walls of the cabinet for guiding said frame in its vertical movement and prevent tilting thereof.

2. A towel cabinet comprising a casing 40 having side walls, and vertical guideways therein, a soiled towel roll and a clean towel roll mounted in said guideways, a frame interposed between said rolls, feed rolls mounted in said frame for engaging respectively said soiled towel roll and said clean towel roll, a driving connection between said feed rolls, a hand grip mounted in one of said rolls, the adjacent side wall of said casing having a vertical slot therein 50 wherein said hand grip is movable to allow the rise and fall of said frame and feed rolls.

3. A towel cabinet comprising a casing 55 having guide-ways therein, a soiled towel roll and a clean towel roll movable in said guide-ways, feed rolls mounted to contact respectively with said clean towel roll and said soiled towel roll for driving them simultaneously, a loop of towel from the clean 60 towel roll being extended between said roll and the back of the cabinet to the soiled towel roll, and bars vertically arranged in the rear of the soiled towel roll and between which bars and the wall of the cabinet the 65 soiled towel is fed to said soiled towel roll.

In witness whereof, I have hereunto set my hand this 4th day of May 1920.

GEORGE ADOLPH STEINER.
